ATTORNEY

UNITED STATES PATENT OFFICE.

JAMES LEO, OF JERSEY CITY, NEW JERSEY.

DESIGN FOR A BOX-TRIMMING.

SPECIFICATION forming part of Design No. 23,942, dated January 1, 1895.

Application filed September 4, 1894. Serial No. 522,119. Term of patent 7 years.

To all whom it may concern:

Be it known that I, JAMES LEO, a citizen of the United States, residing at Jersey City, in the county of Hudson and State of New Jersey, have invented and produced a new and original Design for a Box-Trimming, of which the following is a specification, reference being had to the accompanying drawing, showing the same.

10 *c* In the accompanying drawing A represents a rectangular plane surface on which the design is produced in contrasting shades of color.

15 The design consists of a marginal band, *a*, of uniform width in the form of a rectangular frame, having at its four corners re-entering quadrantal fillets, *a'*, of the same shade and

color as the band *a* and merging with the same. Within the band *a*, is a band, *b*, of lighter shade of color surrounding a central panel, *c*, of general rectangular form, said panel being 20 of a lighter shade than the band *b*.

What I claim is—

The design for a box trimming substantially as shown and described.

In witness whereof I have hereunto signed 25 my name in the presence of two subscribing witnesses.

JAMES LEO.

Witnesses:

HENRY CONNETT,
J. D. CAPLINGER.
